(57) **CLAIM**

The ornamental design for a case for digital camera, as shown and described.

DESCRIPTION

FIG. 1 is a perspective view of the front, left, and top sides of a case for a digital camera showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a front elevational reference view thereof in a condition of the case being placed on the digital camera.

In FIG. 8, the digital camera is shown in broken lines for illustrative purposes only and forms no part of the claimed design.
